CONTROL SYSTEM FOR DOORS

Felton S. Jenkins, Philadelphia, Pa.

Application May 1, 1946, Serial No. 666,471

5 Claims. (Cl. 263—59)

1

This invention relates to control of an operating mechanism by radiant energy, and more particularly to a novel system for remote control by vehicle borne radio of a power driven operator for garage doors.

A principal object of this invention is to provide such a system wherein novel components are interrelated in an improved manner that affords an economy and simplicity heretofore unattainable in prior systems.

Another object is to provide improved radio transmitting apparatus for sending actuating impulses from a vehicle.

A further object is to provide improved radio receiving apparatus for receiving such an impulse and actuating an operating mechanism therewith.

An additional object is to provide an improved door-operating mechanism and power drive therefor.

Another object is to provide means for the selective operation of such a door by radio or manual control.

Equally important objects will plainly appear from the detailed specification and drawings presenting herein a preferred embodiment in exemplification but not in limitation of the present invention. Like reference characters represent like parts in the accompanying drawings which represent diagrammatically in:

Fig. 1: A rear elevation of a novel door assembly embodying the present invention, viewed from the interior of a garage or enclosure.

Fig. 2: A side elevation of the assembly shown in Fig. 1.

Fig. 3: An end view of the motor drive unit, partly in cross section taken on the line 3—3 in Fig. 5.

Fig. 4: A top view of the unit shown in Fig. 3.

Fig. 5: A side view of the unit partly in cross section, taken on the line 5—5 in Fig. 3.

Fig. 6: A side view, partly in cross-section, showing novel disengaging mechanism for operating shaft.

Fig. 7: A wiring diagram representing a novel radio receiving apparatus adapted to actuate universal type electric motor.

Fig. 8: A wiring diagram representing a novel radio receiving apparatus adapted to actuate a single-phase induction motor.

Fig. 9: A wiring diagram representing a novel radio transmitting apparatus adapted to be installed in a vehicle.

The novel control system described herein comprises an electric motor driven work operating

2

mechanism detailed in Figures 3, 4 and 5, for operating a garage door assembly shown for example in Figures 1 and 2, a disengaging device for said mechanism shown in Figure 6, a radio receiver for actuating said motor and diagrammed in Figure 8, a radio transmitting device for actuating said receiver and diagrammed in Figure 9, and a series of diagrammed switches arranged to assure novel and fool-proof operation as illustrated and described herein.

A preferred embodiment of the present invention is illustrated herein particularly in Figures 1 and 2 as applied to the overhead sliding type of garage door 160 that slides in guide rails 118 from its vertical position when closed, to its horizontal position when it comes to rest after it has been opened. Such a door 160 may be formed of sections held in hinged relationship to each other by hinges 161, and is well known in the art as an up and over type of sliding door. The door 160 travels in the rails 118 by means of rollers 180. Guide rails 118 may be supported by braces 184 to garage ceiling 185.

The lower ends of the two tow bars 162 are pivotally attached to the door 160 by pivot means 182 shown in Figure 2, and the upper ends of two bars 162 are pivotally attached to travelling axle shaft 114 of operator 100 by collar 181. Tow bars 162 may be adjusted for length by turnbuckle means 163.

As will be subsequently described, this type of door 160 is operated by an induction motor 61 as shown in Figure 8 which drives the operating mechanism 100.

35 *Operating mechanism*

The door operator 100 detailed in Figures 3, 4 and 5 includes an electric motor 61, arranged to drive a travelling nut member 103 along threaded shaft 104, and thereby pull door 160 open, or push it closed by means of its tow bars 162.

Motor 61 is attached to the motor cradle 106 by means of the bracket 119 and is provided with motor pulley 120 which drives the driving tube pulley 110 by means of belt 121. Cradle 106 is in the form of a downwardly suspended swinging pan provided with opposed inwardly projecting sleeve members 107 which ride in pillar blocks 108. These pillar blocks 108 are attached to carriage member 105 by bolts 113. Riding in the sleeve member 107 is the driving tube member 109 which surrounds the threaded shaft 104. To the forward end of the tube 109 is connected a drive pulley 110 and to the rear end of the tube 109 is connected the nut member 103 held on the

tube 109 by means of set screw 111. Thus nut member 108 is thereby readily detachable and replaceable.

Carriage 105 is supported by axle member 128 which passes through apertures 115 in carriage 105. Carriage 105 is held in position on axle 128 by means of collars 116 fixed to the axle 128 by means of set screws. Each outward end portion 114 of the axle 128 is fitted with wheel members 117 adapted to ride in the rails 118 as shown in Figure 1. Axle ends 114 are arranged to telescope into the larger axle sections 128 so that the span between the wheels 117 may be adjusted to accommodate various distances between the rails 118. Overload switches 59 are shown mounted on carriage 105, so that they will be actuated by the swing or tilt of cradle 106. They may, if desired, be conversely mounted on cradle 106 and positioned so that when motor 61 tilts they will be actuated by contact with carriage 105. Limit switch 56 and reversing switch 55 are mounted on axle 114, as shown in Figure 3.

The forward end of the shaft 104 is anchored in the front wall 164 of the garage by the disengaging means 165 shown in Figure 6 and the rearward end of the shaft 104 is supported by, but not fixed to, a transverse strut member 112. Strut 112 is fixed to and spans rails 118 as shown in Fig. 2. This permits the rear end of the shaft 104 to have limited free movement on and above strut 112.

The axle 114 is provided at one extremity with reversing switch 55 as shown in Figure 1 which is actuated by a stop or tripping mechanism 126 positioned so as to actuate the reversing switch 55 at the end of the rearward travel of the axle 114 on the rails 118.

The other end of the axle 114 is provided with limit switch 56 arranged to be actuated by a tripping mechanism 126 positioned at both extremities of travel on the rails 118.

Referring again to Figure 3, a dash pot device 140 is provided to control and dampen the speed of the swing in the pendulum action of the motor cradle 106 when obstruction causes any overload on the motor 61. The dash pot 140 is constructed of a cylinder 141 and a piston 142 connected to a shaft or piston rod 143 provided with a pivotal connecting means 144 and permanently fastened to a bracket 145 which is mounted on the motor cradle 106. The end of the dash pot 140 opposite bracket 145 is fastened by means of a hinge 146 to the carriage 105 of the operating mechanism 100. The dash pot 140 includes a fluid passage 147 with two orifices 148 at each end of the cylinder 141. One of the two orifices 148 is provided with a needle valve 149 to control quantity of fluid passing from one side of the piston 142 to the other and thereby controlling the desired dampening effect on the pendulum action of the motor cradle 106.

Motor overload protection switches 59 and limit switch 56 are single pole normally closed push plunger type snap action. These switches operate only when the cradle is caused to swing out of its normal position as a result of obstruction to the door or to the operating mechanism. The swinging motion of the cradle actuates either of the switches 59 and momentarily breaks the circuit to the motor 61 causing it to stop. This interruption causes the starting field of the induction motor 61, shown in Fig. 8, to cut in, the field then being in a reverse starting position, due to the operating position of the reversing switch 55 at that point of travel.

Reversing switch 55 is a double pole double throw lever type snap action switch with spring return arranged and connected so that in the normal position of its lever it will cause the door to open when current is applied to motor 61. When the lever is actuated by trip mechanism 126 and power applied door 160 will close.

In Figure 7 where a series wound motor 54 is used, the reversing switch actuating mechanism is mounted on the track at each end of travel, thus providing actuating means for reversing motor direction simultaneously with the action of limit switch 56.

A double pole double throw reversing switch 55 shown in Figure 8 is mounted on axle 114 adjacent rail 118 and is positioned to be actuated by a tripping mechanism 126 mounted on rear end of rail 118.

When limit switch 56 is mounted on the axle 114, one is sufficient, but if mounted on the rail 118, two will be used mounted at each end of door travel, and wired in series with each other.

A source of normal house current is shown in Figures 7 and 8 at 53 which may be 110 or 120 volts. The operating motor indicated in Figure 7 at 54 is preferably from $\frac{1}{20}$ to $\frac{1}{4}$ H. P., depending on the type of door and the rate of travel desired for the door. The motor 54 and the apparatus described in Figure 7 is preferred for small swinging-type garage doors.

For the overhead type sectional sliding doors a single phase induction type motor 61 of $\frac{1}{8}$ to $\frac{3}{4}$ H. P. shown in Figure 8 is preferred, depending on weight of door and desired speed of transit. This type of motor permits the reversing switch 55 to be connected only in series with the starting field of the motor. Therefore, switch 55 can be actuated after the motor is started and is in action, to a reverse position without affecting the operation of the motor 61. This requires a tripping mechanism 126 shown in Figure 1 on only one end of the travel, at the rear end of the rail 118.

The conduit 124 comprises the power supply leads, and conduit 123 comprises the control leads. Additional branches of the control leads 123 can be installed at any desired remote control location such as the push button 129 shown in Figure 1. The control box 122 containing the radio receiving unit shown in Figure 8 is connected to the motor 61 by means of the conduit 123. The power from source 53 is fed into the control box through the leads 124 and reaches the motor through the flexible suspended conduits 125 for connection to motor 61, shown in Figure 2.

Receiver

The receiving apparatus 122 shown in Figure 1 and indicated by the wiring diagrams in Figure 8, includes a receiving antenna 30 grounded as shown at 40. Connected thereto as shown are radio frequency transformers at 31 and 32. At 33 and 34 are variable tuning condensers of the compression type having a preferred range from two to thirty micro-microfarads and are used in tuning the transformers 31 and 32. Shown at 35, is a low capacity, for example a two micro-microfarad negative temperature coefficient ceramic capacitor used to stabilize the frequency of the receiver by compensating for changes in temperature.

Indicated at 36 is a cathode bias resistor of 400 ohms resistance, and at 37 a radio frequency by-pass condenser of .01 microfarad. At 38 is a

screen grid radio frequency by-pass condenser of .01 microfarad, and at 39 is a screen grid voltage dropping resistor 75,000 ohms. At 41 is a radio frequency choke for supplying voltage to plate of tube 45 and permits the plate to swing with the incoming signal.

It is important that the inductance be preferably of a value that will be resonant at the operating frequency. For example, a choke 41 of 2.5 millihenries with 4 II's (coils) will have a resonant frequency of approximately seven megacycles when used with a 100 micro-microfarad mica coupling capacitor 42, feeding the signal into the primary of the succeeding radio frequency transformer 32.

At 43 is indicated a 3 megohm grid leak resistance connected in parallel with a 100 micro-microfarad mica capacitor 44, which assists in rectification of the incoming signal.

A tube 45 of the radio frequency pentode type is used in the first radio frequency stage of the receiver, the output of which feeds into a high μ triode type tube 46, known in the art as a detector.

A sensitive relay 47 operates on a current differential of one-half of one milli-ampere and is provided with 5-ampere contacts shown at 48 with single pole double throw action.

A 25 microfarad (or larger depending on duration of delay desired), 25 volt electrolytic condenser is shown at 49, which charges and discharges at a slow rate and permits only direct current in the coil of the relay 47, and also prevents the relay 47 from chattering during the negative half cycle of the power frequency. The condenser 49 also provides the necessary time delay action to prevent the actuation of the device by static or other momentary atmospheric disturbances, or other sources.

A filament supply stepdown transformer 50, provides the necessary filament voltage for the tubes 45 and 46.

At 51 are shown bypass condensers arranged to bypass any radio frequency voltage from the power line to the ground 49 which in this case is the chassis of the receiving set itself. At 52 is shown a thermo bi-metal time delay switch used to provide the time delay action and electrically causes an open current in the sensitive relay contacts 48 thus preventing said relay from actuating the door operating mechanism until the receiving tubes 45 and 46 filaments have heated and provided normal operation of the receiving unit.

The induction motor 61 shown in Fig. 8 draws considerably higher current for its starting torque than the universal motor 54 in Figure 7. When this higher current is in excess of the current rating of the sensitive relay contacts 48 a secondary relay 60 shown in Figure 8 is provided with contact ratings suitable for the size motor used and arranged to be actuated by the sensitive relay 47 as shown in Fig. 8.

It is important to note that the choke 41 and the condenser 42 previously described herein are used to stabilize and isolate the two radio-frequency stages which avoids the added complication of shielding. They also increase the overall sensitivity of the receiving apparatus inasmuch as sensitivity is required on only one frequency in the present invention.

Figure 7 is included to complete the disclosures of the electronic part of the novel control system presented herein and represents a receiving device preferred for use for double vertically

swinging doors in which the improved operating mechanism 100 described herein need not be employed. Double swinging doors require a series wound so-called universal type electric motor 54 which because of the nature of operation of the swinging door does not have to be arranged to travel. It can be fixed to the ceiling of the garage and therefore does not require the type of limit switches required by the travelling motor 61, described herein.

Among the important advantages of the novel receiver described herein are, first that the whole circuit is resonant at the operating frequency which assures ample sensitivity. Next, novel frequency stability is provided at 31, 32, 35, 41 and 42 as previously described, and the novel design permits amazingly low power consumption comparable to that of an electric clock and simplicity due to air core construction of the transformer and elimination of shielding. Assurance against the adverse effect of temperature change is provided at 33, as set forth herein. This novel design attains the utilization of low plate current and permits long tube life. By the elimination of coil forms and the utilization of air dielectric cores in 31 and 32 current losses are unexpectedly low. The novel receiver herein-described permits operation on any frequency between the ranges of 500 kilocycles to 200 megacycles. Transformers 31 and 32 may be wound for any one of the frequencies in the aforementioned range and can be utilized in the circuit without any circuit variations.

The novel application of low plate current (one milli-ampere or less) in the tubes 45 and 46, and the rating of 35 milli-amperes on the tubes, affords trouble free operation and years of life without changing tubes.

The novel receiver described herein affords a stability hitherto unknown. It is unaffected even at high frequencies, by atmospherics, or by disturbances originating in motor vehicles, city light lines, or by voltage fluctuations of any nature.

In order to prevent the unauthorized operation of the electronic control by a strange transmitter each receiver unit is designed to operate within a given range determined at the factory. This may be any one of 8,000,000 different frequencies.

Any attempts to determine the frequency for any given installation will prove futile not only because of the vast range of frequencies but also because of the time delay action of the capacitor 49 connected in parallel with the sensitive relay 47 which would prevent detection by anyone searching by means of a variable frequency oscillator and other searching means known in the art.

Transmitter

The transmitter preferred for installation in the vehicle comprises a novel improvement on what is known in the art as a Hartley type oscillator indicated at 70 in Figure 7. It includes a tuning inductance 71, wound for the desired frequency, and a variable tuning capacitor 72 of the compression type arranged for tuning the inductance, with a capacitance range, from 2 to 30 micro-microfarads. Included also are the necessary coupling condensers 73, a 75,000 ohm grid leak 75, a 100 micro-microfarad grid condenser 74, a radio frequency choke 76, and a temperature compensating capacitor 101.

The tube 77 is a filament type, having a filament voltage rating equivalent to the voltage of the car battery, and which heats up almost instantly when filament circuit is closed. Tube 77

may be connected directly across the vehicle or automobile battery by means of push button switch 79, mounted on the dashboard of the vehicle and connected in series with the filament of tube 77, through terminals A- and A+ shown in Figure 9.

The direct current plate supply for the tube 77 is supplied preferably from a 22½ or 45-volt B battery preferably located in the glove compartment of the automobile, and connected through terminals B-, and B+, shown in Figure 9.

The antenna 81, may be the existing automobile radio antennae, or it may be any other metal object on the automobile, providing it is properly insulated from the frame of the car, mounted on the exterior of the car, and has sufficient radiating surface.

Anchoring device

The anchoring device 165 detailed in Fig. 6 and indicated in Fig. 2 comprises an anchor block 166 bolted, for example, by bolt 167 to the inside of the front wall 164 of the garage. The block 166 is provided with a rectangular recess 168 adapted to receive the squared end portion 176 of the threaded shaft 104. The end portion 176 is provided with an angular notch 175 adapted to engage the latch 174. Anchor block 166 is provided with a cylindrical recess 170 adapted to receive the sliding latch pin 171, and with a spring recess 169 to receive the latch pin spring 173. The pin 171 is preferably provided with a chain 172 arranged to hang within reach of occupant of garage.

When it is desired to disengage the operating mechanism 100 so that the door 160 may be temporarily operated by hand, due to power failure or other causes, the latch pin 171 is pulled downwardly so that latch clears notch 175, thereby releasing shaft 104 so that it will slide out of engagement with recess 168. As the other end of shaft 104 rests freely on strut 112, the manual operation of the door is readily accomplished and the resulting travel of door 160 will cause shaft 104 and mechanism 100 to travel with door 160. When mechanical operation is again desired, the end portion 176 is inserted in recess 168 and is latched therein by action of spring 173 and latch 174.

Operation

The operation of the novel control system described herein is as follows:

When the driver of the vehicle approaches within range of the door of the garage or enclosure usually 2 to 50 yards, and desires to open the door, he holds down the button 79 on the dashboard, preferably from one to two seconds. This energizes transmitter 76 as described herein, and indicated in Figure 9, which in turn generates a radio frequency wave and feeds it to antenna 81. This wave signal, or impulse, is radiated by transmitting antenna 81, and is received by receiving antenna 80. This signal is then amplified and rectified as described herein and causes relay 47 to be actuated. The contacts 48 of relay 47 then supply the necessary power from source 53, to motor 54, as shown in Figure 7. If motor 61 is used as shown in Figure 8, the relay 47 actuates secondary relay 60 which in turn supplies power to the induction motor 61.

When the door is in closed position and before the impulse is received, the limit switch 56 is depressed by the trip 126 and the circuit to the motor is held open thereby. This is also true when door is resting in its open position. When

the impulse is received limit switches 56 (but not overload switch 59) are by-passed or shunted out by action of secondary relay 60 shown in Figure 8, or sensitive relay 47 shown in Figure 7, thereby causing motor to start. When motor moves door away from the contact position of trip 126, the limit switches 59 close and automatically assume the duty of supplying current to the motor, while the relay 47 returns to the "no signal" normal position. Pulley 110 driven by the motor rotates nut 103 by means of tube 109, causing nut 103 to travel along shaft 104, carrying operating mechanism 100 and door 160 therewith as previously described.

When the door 160 has reached the end of its opening travel, trip 126 actuates limit switch 56, opening the circuit and stopping the motor, and the travel of the door 160.

To close the door 160 the driver of the vehicle again depresses button 79 for a like period, and the above operation is reversed. In the event of any obstruction to the closing travel of the door the operation of operating mechanism 100 is as follows:

The obstruction causes added load on operator 103 which in turn causes motor 61 to gradually swing outwardly at right angles to line of travel by means of the suspension of cradle 100 in the pillar block 108, mounted on carriage 105. The force to cause this swing is generated by the ratio of the diameter of pulleys 110 and 120. The greater diameter of pulley 110, causes the motor to tend to climb belt 121 and thereby gradually move out of its vertical position. When the amplitude of this swing is sufficient it momentarily depresses switch 59 and causes motor 61 to stop. The amount of torque is governed by the adjustment of valve 149 and the weight of the motor. Valve 149 controls the speed of swing and prevents the starting torque of motor 61 from causing oscillation, at start of operation. Furthermore the swinging suspension of carriage 105, on axle 128 permits installation without tedious alignment, and affords the advantage of anchoring shaft 104 at one end only as shown in Figure 9 at 166, and permitting the free movement of the other end of shaft 104 on strut 112 thereby assuring simple and economical installation. The fact that the shaft 104 does not revolve, also eliminates the problem of whipping action in the shaft and thereby reduces costly bearing friction and repairs.

It is important to note that the present invention has eliminated costly and complicated mounting for operating mechanism 100. It is self-contained and is applied directly to the door installation as herein described. This affords simplicity in installation as well as in construction.

The present invention is not limited to the preferred example illustrated and described herein, but is intended to include all embodiments and modifications thereof within the spirit and scope of the appended claims.

What is claimed is:

1. A control system of the class described comprising in combination, a radio transmitter, a door arranged to travel on overhead rails, an electric motor driven operator arranged to travel on said rails for opening and closing said door, a source of electric current for said motor, a radio receiver arranged to apply said current to said motor when actuated by a signal from said transmitter, automatic means for stopping said motor and said operator at the end of travel of said

door, automatic means for stopping said motor and said operator upon obstruction of said operator during travel of said door and said operator, said last named means including a nut rotated by said motor for reciprocating travel on a non-rotating threaded shaft, drive means between said motor and said nut, said motor being swingably suspended below said shaft, switch means arranged to be actuated by the swinging action of said motor, said drive means being arranged to cause said motor to swing upon obstruction to travel of said operator on said shaft.

2. The system described in claim 1 wherein said operator comprises means connecting said operator to said door, transverse axle means arranged to travel on said rails, a longitudinally disposed threaded shaft member held at its forward end by said release means and supported at its rearward portion for limited free movement, a carriage member swingably mounted on said axle means, a threaded nut member arranged to rotate on said threaded shaft, nut mounting means carried by said carriage, a motor cradle swingably supported by said mounting means, a motor carried by said cradle, drive means connecting said motor and said nut arranged to cause said motor cradle to swing out of its normal position upon obstruction to the travel of said operator, overload switch means arranged to be actuated by said swing to stop said motor, means for dampening said swing during unobstructed operation, and electrical means for limiting and reversing the travel of said operator during normal motor driven operation of said door.

3. The system described in claim 1 wherein said release means comprises an anchor block fixed to said garage, a recess in said block arranged to receive and hold the adjacent end portion of said threaded shaft in a non-rotating

position therein, latch means in said end portion and in said recess arranged when engaged to prevent the withdrawal of said shaft, resilient means normally holding said latch means in its engaging position, and means for manually holding said latch means out of its engaging position.

4. The system described in claim 1, wherein the entire circuit of said receiver is resonant at the operating frequency of said receiver.

5. A control system of the class described comprising in combination, a radio transmitter, a door arranged to travel on overhead rails, an operator unit arranged to travel on said rails for opening and closing said door, an electric motor swingably suspended on said operator, a source of electric current for said motor, a radio receiver arranged to apply said current to said motor when actuated by a signal from said transmitter, drive means connecting said motor and said operator unit and arranged to cause said motor to swing out of its normal position upon obstruction to travel of said unit or said door, and switch means arranged to be actuated by said swing to stop said motor.

FELTON S. JENKINS.
